UNITED STATES PATENT OFFICE

GEORGE S. SMITH, OF PITTSBURGH, PENNSYLVANIA, ASSIGNOR, BY MESNE ASSIGNMENTS, TO PITTSBURGH SCREW AND BOLT CORPORATION, A CORPORATION OF PENNSYLVANIA

STOCK-FEEDING MECHANISM

Application filed May 7, 1925. Serial No. 28,618.

This invention relates to metal working and more particularly to a method and apparatus for feeding and heating stock preliminary to its introduction into a forging or upsetting machine.

In the manufacture of bolts or similar headed articles, stock in the form of wire or a continuous rod is fed into a heading machine by an intermittently operated feed mechanism which generally consists of feed rollers. Prior to being introduced into the machine it is necessary to heat the stock to a forging temperature.

An object of this invention is to provide an improved method of continuously heating wire stock or the like and feeding it to a forging machine.

A further object is to provide a mechanism for continuously heating such stock to a forging temperature as it is fed toward the machine, which mechanism is so constructed and arranged as to enable the use of a smaller heat zone than has hitherto been possible.

A still further object is to provide an improved form of feed mechanism for causing the stock to travel through the heat zone.

A still further object is to provide an apparatus of the type set forth which will be simple and cheap to manufacture and operate, rugged in construction and reliable in operation.

These and other objects which will appear obvious to those skilled in this particular art, are attained by means of this invention, one embodiment of which is shown, for the purposes of illustration, in the accompanying drawings, in which Figure 1 is a diagrammatic plan view of an apparatus adapted to perform this improved method. Fig. 2 is a view thereof in side elevation. Fig. 3 is a top plan view of one form of mechanism for feeding the stock through the furnace, showing its cooperation with and operation by the associated forging machine. Fig. 4 is a view in side elevation of the mechanism shown in Fig. 3. Fig. 5 is a view similar to Fig. 4 showing the opposite side of the mechanism. Fig. 6 is an elevation showing the mechanism for feeding the stock through the heating fur-

nace and Fig. 7 is a vertical transverse section thereof on the line 7—7 of Fig. 5.

The drawings illustrate my invention as applied to the heating and feeding of wire stock to a forging machine such, for example, as a bolt header. A reel of wire stock is supported adjacent one end of a heating furnace, and the wire passes through the furnace in its travel to the upsetting machine so as to be heated to a forging temperature. The customary practice has been to pass the wire through the furnace in a single direction and then feed it directly into the upsetting machine. This necessitates the provision of a comparatively long furnace in order that the stock may be in the heating zone a sufficient length of time to have its temperature raised the required amount.

In order to enable the use of a shorter and smaller furnace than has heretofore been possible, I first pass the wire directly through the furnace in the usual manner. Instead, however, of then feeding the wire directly into the forging machine I pass it around a roller and back again through the entire length of the furnace, thence around a second roller and through the furnace for a third time, after which it is fed into the forging machine in the usual manner. Either roller at either end of the furnace around which the wire passes may be operated as a feed roller for passing the wire through the furnace, but I preferably use the first roller, which is between the furnace and the forging machine, as the feed roller, in order that the same may be operated from and synchronously with the machine itself.

The particular embodiment of this invention which has been chosen for the purpose of illustration is shown in connection with a bolt header or upsetting machine 10 of any desired construction having the usual intermittently operated feed rollers 11 for supplying the machine with wire stock 12. A furnace 13 for raising the stock to any desired temperature is provided adjacent the machine and may be of any desired form, but as above indicated can be substantially smaller in size than the usual furnace, due to this method

of passing the stock therethrough a plurality of times.

A reel 14 of the wire is rotatably mounted at one end of the furnace and the wire is drawn from the reel through the furnace, around a feed roller 15 back through the furnace, around an idler roller 16, thence through the furnace a third time and into the upsetting machine. As indicated above, either of the rollers 15 or 16 may constitute feed rollers, but I preferably form the roller 15, which is at the machine end of the furnace, as a feed roller and operate the same from and synchronously with the machine itself.

The shafts 17 on which the feed rollers 11 of the machine are mounted have the usual gears 18 on the opposite ends, and these gears are intermittently operated to feed the stock into the machine by a large driving gear 19 mounted on a stub shaft 20 which also has secured thereto a gear driving ratchet 21. The ratchet is intermittently rotated by ratchet engaging pawls 22 secured to an oscillating supporting plate 23 loosely mounted upon the stub shaft 20 and which is oscillated by means of an oscillatory crank arm 24 operated from the driving wheel 25 of the machine through a connecting rod 26.

The feed roller 15 is operated in synchronism with the feed rollers 11. A turnbuckle 27 has one end secured to the reciprocating end of the connecting rod 26 by a link 28 and its opposite end is mounted upon a crank pin 29 which is adjustable in a crank arm 30 secured to a shaft 31 mounted in bearings 32 on a housing 33. The opposite end of the shaft 31 has an oscillating toothed segment 34 secured thereto, the teeth of which mesh with teeth formed on a pawl supported plate 35 which is loosely mounted on one end of a shaft 36 supported in bearings 37 on the housing. Pawls 38 are secured to the plate 35 and are adapted to intermittently rotate a ratchet 39 secured to the shaft 36.

Each pawl has an outwardly extending arm 40 whose outer ends are connected by links 41 to a handle 42 pivoted to the pawl supporting plate 35. While the weight of the links 41 and handle 42 are sufficient to ordinarily maintain the pawls in engagement with the ratchet 39, the handle 42 can be raised so as to disengage the pawls from the ratchet to enable adjustment of the mechanism and to permit the wire to be threaded through the furnace and introduced into the feed rolls 11.

The opposite end of the intermittently rotated shaft 36 is provided with a spur gear 43 which meshes with and drives a smaller gear 44 rotatably mounted upon a stub shaft 45 in the side of the housing 33. The gear 44 drives a second gear 46 secured to a shaft 47 extending into the housing 33, and the inner end of which is provided with a bevel gear 48 meshing with a similar gear 49 secured to a vertical shaft 50 which extends through a

bearing 51 in the top of the housing, and to the upper projecting end of which is secured the wire feeding roller 15.

The vertical shaft 50 is provided with a spur gear 52 which drives a similar gear 53 secured to a second vertical shaft 54 which is supported in horizontally movable bearing blocks 55. A pinch roller 56 is mounted on the upper projecting end of the shaft 54 and is adapted to press the stock into driving engagement with the feed roller 15 so as to prevent any slipping of the stock on the roller. A spiral spring 57 is compressed between each bearing block 55 and a spring plate 58, slideable in a groove 59 formed in a plate 60 secured to the side of the housing. Each plate 58 is adjustable toward and from the movable bearings 55 by means of threaded members 61 which are threaded in the supporting plates 60 and whose outer ends are provided with cranks 62. By varying the position of the plates 58 the pressure of the springs upon the movable bearings can be increased or diminished so as to control the pressure of the pinch wheel 56 upon the stock as it passes around the roller 15. The mesh of the gears 52 and 53 is sufficiently loose to permit the slight adjustment necessary.

In operation a reel 14 of stock is rotatably mounted upon a movable supporting arm 63 and the wire is drawn through the heat zone of the furnace, around the feed roller 15, back through the heat zone, around the idler roller 16, through the heat zone for a third time and is thence fed by means of the feed rollers 11 into the heading machine. The feed roller 15 is intermittently operated in synchronism with the rollers 11 and by the same driving means which operates the latter rollers. In starting the operation the wire can be drawn around the feed roller 15 and the latter rotated independently for this purpose by disengaging the pawls 38 from the ratchet 39 through the medium of the handle 42, after which release of the handle 42 will move the pawls 38 into engagement with the ratchet 39. Preferably the feed roller 15 is driven slightly ahead of the feed rollers 11 so as to provide sufficient slack of the stock in the furnace to eliminate tension thereon and thus reduce the load on the feed rollers 11. When the reel of wire has been exhausted the reel 14 is removed from the supporting arm 63 and the end of the wire is butt-welded, for example, by an electric welder 64, to the end of the wire 120 on a fresh wheel 65 which is supported on the opposite end of the arm 63. The latter arm is rotatably mounted on the base 66 so that it can be rotated to move the fresh reel 65 into position adjacent the furnace. The empty reel 14 is removed and a full one put in its place so that the operation can be repeated at the proper time.

By feeding the wire through the furnace a plurality of times I am enabled to use a sub-

stantially smaller furnace than has hitherto been possible. The feed roller 15 relieves the machine feed rollers 11 of the load of the wire passing through the furnace and it is operated synchronously therewith by the same driving mechanism so that the feed of the entire length of wire is easily accomplished without undue strain.

Although I have described and illustrated 10 a particular embodiment of this invention it will be understood that various modifications, additions, substitutions and omissions can be made without departing from this invention or the scope of the appended claim.

15 What I claim as new and desire to secure by Letters Patent is:

The combination with a forging machine provided with stock feeding mechanism including a feed operating lever arm operated 20 by said machine, of an associated heating furnace for heating stock fed to said machine and means for feeding stock through said furnace including a feed roll, a pawl and ratchet drive for operating said feed roll, an adjustable crank for operating said pawl and ratchet and a turnbuckle connecting said 25 crank to said lever arm.

In testimony whereof, I have hereunto subscribed my name this 5th day of May, 1925.

30 GEO. S. SMITH.
